UNITED STATES PATENT OFFICE.

OMER DEAKINS, OF MOUNT STERLING, KENTUCKY.

WASHING-MACHINE.

1,151,444.

Specification of Letters Patent. Patented Aug. 24, 1915.

Application filed November 7, 1914. Serial No. 870,906.

To all whom it may concern:

Be it known that I, OMER DEAKINS, a citizen of the United States, residing at Mount Sterling, in the county of Montgomery and State of Kentucky, have invented new and useful Improvements in Washing-Machines, of which the following is a specification.

This invention contemplates the provision of a washing machine in the nature of a boiler wherein the boiling water and steam is forced in a continuous circulation through perforated vertical and horizontally disposed communicating conduits, and discharged on all parts of the clothes completely sterilizing the same in a comparatively short time.

Among other features the invention embodies simplicity of construction, the parts being readily and easily removed for cleansing the same, whereby the machine can be kept perfectly sanitary.

Other objects will appear from the following description when taken in connection with the accompanying drawings, the invention residing in the construction, combination and arrangement of parts herein-after more fully described.

In the drawing forming a part of this application like numerals of reference indicate similar parts in the several views and in which:

Figure 1 is a vertical sectional view. Fig. 2 is a horizontal sectional view. Fig. 3 is a detail perspective view of the removable bottom. Fig. 4 is a view of the inner casing partly in section.

My improved machine consists essentially of an outer section 5 preferably of rectangular formation but which can be made in any suitable contour, having a bottom 6, and suitable handles 7.

Snugly fitted within the outer section 5 is a bottomless inner section 8 corresponding in shape to the contour of the section 5.

Secured in any suitable manner to each of the four sides of the inner section 8 and adjacent the lower edge thereof are horizontally disposed flanges 9 upon which rests the vertically disposed conduits 10 the latter being closed at their upper ends by the inwardly directed flange 11 forming a continuation of the respective sides of the sections 8. The vertical conduits 8 as shown in this particular instance are substantially U-shaped in cross section, having the free edges of the parallel portions 12 soldered

or otherwise secured to the sides of the section. As shown one of these conduits is secured to each side of the section and are disposed directly opposite each other, although any number of these conduits may be employed to accommodate different size machines. The flanges 9 are cut away immediately below each conduit 10 as at 13, forming an inlet through which the hot water and steam enters the conduits, and is forced upwardly and discharged in a spray through the apertures 14 arranged in longitudinal series on the central portion 15 of the conduits.

Extending entirely around the sides of the inner section 8 slightly above the transverse center thereof is a horizontally disposed series of aligned conduits 16 of substantially U-shape in cross section, having the free edges of the parallel portions 17 suitably secured thereto. The adjacent ends of the horizontal conduits 16 engage against the opposite parallel portions 12 of the vertical conduits 10 and communicate therewith through suitable openings 18 formed in the said parallel portions 12, the conduits 16 being also provided with a longitudinal series of apertures 19. The opposite ends of the horizontally disposed conduits 16 engage against the sides of the vertically disposed corner conduit 20 and communicate therewith through suitable openings 21, the corner conduits being substantially V-shaped in cross section as shown and having their apices provided with a vertical series of apertures 22.

By reason of this construction it will be obvious that I provide for a continuous circulation of hot water and steam through the various conduits, which is discharged through the apertures formed therein in a spray that penetrates all the clothes in the boiler with the most effective results, completely sterilizing the same in quick order. The water in the return circulation finds its way to the space below the removable bottom 23 through the apertures adjacent the lower end of each of the vertical conduits 8.

Seated upon the flanges 9 is a removable bottom 23 having an apertured collar 24 depending centrally therefrom and engaging the bottom 6 of the casing 5. The removable bottom has a central opening from which rises the apertured tube 25, which communicates with the outer casing 5 and is closed at its upper end. The hot water

and steam is also forced upwardly through this tube and discharged through the apertures upon the clothes.

A short shaft 27 is removably journaled in an aperture 28 in the cover 29 and has its upper end projected through the bracket 30 and is squared or otherwise splined for non-rotatably receiving a turning wheel 31 provided with a handle 32. The bracket is formed with radiating arms 33 secured to the cover by means of the fastening elements 34. The lower end of the shaft is enlarged as at 35, and in which is inserted the free ends of the spider arms 36, each pair of arms being formed from a single strand of wire. With this construction the clothes in the boiler can be stirred about when necessary without removing the cover.

The cover 29 is formed with a depending flange 37 which rests upon the flanges 9 of the inner section 8, the latter being disposed slightly below the upper edge of the outer section 5. 39 indicates a faucet for removing the water from the outer section when finished washing.

From the foregoing description it is believed that the nature and advantages of the invention will be thoroughly understood without requiring a more extended explana-

tion and therefore the same has been omitted.

What I claim is:—

A washing machine comprising an outer casing, an inner bottomless casing removably fitted therein and having horizontal flanges disposed immediately above the bottom of the outer casing, vertically disposed apertured conduits rising from said flanges and having their lower ends in communication with said outer casing, the said inner casing terminating at its upper edges to provide inwardly directed flanges closing the upper ends of said conduits, a flat removable bottom supported upon said lower flanges, an apertured tube rising centrally therefrom and having communication with said outer casing, an apertured collar depending from said removable bottom and disposed therebetween and the bottom of said outer casing, and a cover having a depending flange resting upon the said inwardly directed flanges of said inner casing.

In testimony whereof I affix my signature in presence of two witnesses.

OMER DEAKINS.
